TIMING MECHANISM

Ervin H. Mueller, Grosse Pointe, Mich.

Application August 23, 1950, Serial No. 180,957

1 Claim. (Cl. 161—7)

1

This invention relates to a mechanism for timing an operation. The mechanism may be advantageously employed in determining the time that a valve is opened and in this connection, the mechanism may be employed with a valve for controlling the flow of gas to a burner of a gas range or other heating or cooking equipment.

The objects of the invention include the provision of a simple mechanism with a minimum number of parts so that the action is sure and positive in its function. The mechanism is associated with a controlled element which may be spring pressed and when the mechanism is set for its operation, the spring pressed control element is held in a position against the action of the spring. At the end of the determined time the mechanism releases the controlled element completely so that the controlled element may shift under the action of its spring entirely independent of the mechanism. Thus, the controlled element need not be arranged and constructed so as to shift or actuate any of the timing mechanism. The controlled element may be a valve normally spring pressed to closed position and which is held open by the timing mechanism and which is completely released by the timing mechanism when the valve is to be closed.

A timing mechanism constructed in accordance with the invention is disclosed in the accompanying drawings:

Fig. 1 is an elevational front view of such a mechanism.

Fig. 2 is a side elevational view thereof.

Fig. 3 is a view looking into the mechanism with the bell of the timer removed and showing some valve parts in section.

Fig. 4 is a view similar to Fig. 3 illustrating the mechanism in another position.

The construction may embody a suitable support 1 with a face 2 having indicia thereon constituting a dial. The indicia shown may be in increments of minutes. The structure may be mounted by means of projections 3 and it has an operating handle 4.

Mounted on the rear of the support is a suitable bell 7 which may be held by a screw 8. Within the bell there is a suitable mechanism in the nature of a clock or watch movement which may be mounted on a bracket 9 and the handle 4 is mounted on and operates a shaft 10 on which is mounted what may be termed a cam element 11 of disc form provided with a notch 12. The screw 8 for holding the bell may be positioned on the same axis as the shaft 10 and may be threaded into a bracket 14 which is cut away as Figs. 3 and

2

4 are viewed in order to expose the mechanism. The bracket 14 is mounted on a frame piece 15.

A valve for controlling flow of gas is shown at 20 and it may be attached to the bracket 1 on the back side thereof. It has an extension 21 providing a chamber 22 and an extension 23 providing a chamber 24. The extension may be internally threaded for connection to gas conduits 25 and 26. Usually, the gas may be entered through the conduit 25 and pass out through conduit 26. The chambers 22 and 24 meet each other at right angles in the valve indicated and it has a valve seat at 28. A valve member is positioned in the chamber 22, the valve member being in the form of a disc 30 with suitable material for engaging the seat 28 and it is acted upon by a coil spring 31 which reacts against a fitting 32 threaded to the valve body. The valve member has a stem 33 slidably disposed in the valve body and projecting out through a passage 34 and having an exposed head 35. A suitable seal may be employed as at 36 to prevent escape of gas around the stem. It will be apparent how gas may flow through the valve when the valve member is spaced from its seat as shown in Fig. 3, and how the flow of gas is stopped when the valve member engages and rests upon the seat by the action of a spring 31.

For controlling the valve there is a lever 40 pivotally mounted as at 41 on the support 9 and having an abutment or pin 42 for engagement with the cam 11. A coiled spring 43 anchored at one end to the support 9 and at its other end to the lever normally holds the lever with the pin 42 engaged against the periphery of the cam 11. A bell hammer 45 pivotally mounted as at 46 is positioned to be engaged by an angularly disposed end portion 47 of the lever 40.

There is a projection or finger on the lever 40 which extends laterally therefrom as indicated at 48. This projection and the lever may be formed of one integral piece of metal. As indicated the proximal end of the projection or finger connects to the midportion of the lever and the finger extends in a direction transverse to the direction of extent of the lever and its distal end is in the form of a foot 49 for engaging the head 35 of the valve stem. The finger passes through an opening 50 in the bell. The projection or finger 48 is guided for movement between the frame member 15 and a bracket 51, it being understood that the guiding bracket is spaced from the frame member 15 for free movement of the projection 48. The bracket thus prevents the spring 43 from cocking the lever on its pivot 41.

In the operation of the mechanism a normal inoperative condition of the parts is illustrated in Fig. 4. The spring 43, in this position, holds the lever arm upwardly with the pin 42 seated in the notch 12 of the cam. The hammer 45 is elevated but it rests upon the lever and is free of the bell. The finger 48 is in a position so that the foot 49 is clear of and spaced from the head 45 of the valve stem. To set the timing mechanism the operator grasps the handle 4 and turns it counter-clockwise as Fig. 1 is viewed. This turns the cam 11 and the parts may be positioned as shown in Fig. 3. In this action, the cam forces the pin out of the notch 12 so that the lever is lowered against the action of its spring and the finger 48 has a swinging action with the lever in a downward direction as Figs. 3 and 4 are viewed. The foot 49 engages the head 35 of the valve stem and pushes the valve member downwardly thus disengaging the valve member from its seat. Thus the valve is opened and gas may flow therethrough.

The valve will be held open as long as the lever is held in the position shown in Fig. 3. The handle 4 and cam 11 may be turned and the mechanism then drives the shaft 10 and rotates it counter-clockwise as Fig. 3 is viewed. In this action, the periphery of the cam rides on the pin 42 and when the recess 12 comes into alignment with the pin the spring snaps the lever upwardly to the position shown in Fig. 4. This is a quick snapping action and the hammer is impelled against the bell causing it to ring. The finger or projection 48 releases the valve and the valve instantly closes under the action of its spring 31.

The time period during which the valve is held open may be determined by the extent to which the cam is turned from the Fig. 4 position as may be indicated by the dial. When the valve is held open the finger 48 acts in the manner of a strut, with the force of the spring 11 being transmitted lengthwise through the finger 48 and thence into the shaft 10. At the end of the time period the entire controlling mechanism snaps upwardly under the action of its spring 43 thus entirely freeing the valve spring, so that the valve is closed independently of the controlling mechanism. In other words, the valve spring is not

called upon to shift anything other than the valve itself and the stem end is not called upon to move any of the controlling mechanism.

I claim:

5 In a timing mechanism for a valve having a reciprocably movable valve member, said timing mechanism having a rotary cam member with a concentric peripheral portion with a notch therein, the axis of the cam member being disposed transversely of and substantially in alignment with the projected path of reciprocation of the valve member, means for driving the cam member, means for setting the driving means into operation and for positioning the cam member; a lever, a pivot for the lever spaced laterally from the projected path of reciprocation of the valve member, a part on the lever for engaging the cam member, a spring acting upon the lever to hold said part against the cam member, said lever being disposed between the valve member and the axis of the cam member, and a finger rigidly on the lever and projecting transversely therefrom toward the valve member, the distal end of the finger being arranged to engage the movable valve member when said part of the lever engages with the peripheral portion of the cam member to hold the valve open, said finger, when holding the valve open, lying substantially in alignment with the projected path of reciprocation of the valve member, whereby the finger acts as a strut, said part on the lever being engageable in said notch when the notch aligns therewith for movement of the lever and movement of the distal end of the finger laterally of the reciprocable path of the valve member, to thereby disengage the valve member for the closing of the valve.
